UNITED STATES PATENT OFFICE.

KARL L. LEHMANN, OF CHICAGO, ILLINOIS.

DESIGN FOR A MONUMENT.

SPECIFICATION forming part of Design No. 21,956, dated November 1, 1892.

Application filed September 8, 1892. Serial No. 445,389. Term of patent 14 years.

To all whom it may concern:

Be it known that I, KARL L. LEHMANN, a citizen of Norway, residing at Chicago, in the county of Cook and State of Illinois, have invented and produced a new and original Design for Monuments, of which the following is a specification.

The accompanying drawing represents an elevation of a monument constructed in accordance with my new and original design.

The leading feature of my design consists of a structure winding about a vertical axis in a spiral course from base to summit and supported only at its base.

As shown in the drawings, the base A of the monument is extended from the lower end of the spiral structure and has an ornamental railing *a* at the edge of a foundation. The spiral structure or monument proper B has a spiral gallery having an ornamental railing *b* on one side and a terrace C, with flowers, shrubbery, &c., on the other side.

Outside the railing *b* are hanging gardens B'. Observation - platforms D, with ornamental railings, are supported on the monument at 25 intervals, and at the top of the structure is a pavilion E, carrying a flag F. The terrace is shown as having ports or doorways G, and the platforms D are shown as having steps H.

A monument made in accordance with my 30 new and original design presents an imposing, graceful, and attractive appearance and is especially designed as a decoration for parks and pleasure-grounds.

I claim—

The design for a monument, substantially as herein shown and described.

In testimony whereof I have hereunto subscribed my name.

KARL L. LEHMANN.
